Patented Oct. 18, 1921.

UNITED STATES PATENT OFFICE.

LAVERN BORDWELL, OF NEW YORK, N. Y.

BEATER.

1,393,941.

Specification of Letters Patent.

Patented Oct. 18, 1921.

Application filed January 18, 1915. Serial No. 2,938.

To all whom it may concern:

Be it known that I, LAVERN BORDWELL, a citizen of the United States, residing at New York city, in the county of New York 5 and State of New York, have invented certain new and useful Improvements in Beaters, of which the following is a specification, reference being had therein to the accompanying drawing.

10 My invention relates to improvements in beaters the primary object of which is to devise a beater comprising beater-blades and actuating means therefor which will be of simple construction and at the same time 15 durable and easy to operate.

The invention particularly relates to an improved manner of constructing the beater-frame upon which are mounted actuating means and beater-blades so that all parts of 20 the frame will be rigid and thereby insure a true alinement of the beater-blades and actuating means whereby these parts will operate to the best advantage.

Heretofore beaters have been made very 25 similar to the present device, but they have all been open to the following defects:

First: When made of simple construction they were not durable.

Second: The framework when under the 30 stress of the operation of beater-blades and operating mechanism would bend and twist so that these mechanisms would be thrown out of alinement and the perfect operation of the beater materially hampered.

Third: In very large beaters where the 35 framework was of greater size even greater difficulties were encountered both as to bending and twisting of the framework and also in the disarrangement of the actuating 40 mechanism in relation to the beater-blades which are driven thereby.

Applicant's invention though of simple construction, and though cheap to manufacture overcomes the above noted difficulties.

Further objects and advantages of the present improvement will be set forth in the following description and appended drawings in which,

50 Figure 1 is a side elevation of my improved beater showing beater-blades and an actuating means mounted upon my improved framework.

Fig. 2 is a detail fragmentary perspective 55 view of a portion of the beater framework.

Fig. 3 is a perspective view of the wire

support upon which the beater-blades are mounted.

Fig. 4 is a perspective view of a modified form of beater framework showing the 60 beater-blades actuating means and handle removed therefrom.

Fig. 5 is a detail enlarged perspective view of the clamp used in connection with the modified form shown in Fig. 2.

Fig. 6 is an enlarged sectional view of the 65 top of the supporting wire shown in Fig. 2 of its connection with the beater-frame.

Fig. 7 is a sectional view taken on the line 7-7 of Fig. 5.

Referring now to the drawings in which like reference numerals designate similar parts, 1 represents the beater framework carrying at its upper end a handle 2, and at its lower end a substantially U-shaped portion 75 consisting of two vertical walls 3 and 4 and one horizontal wall 5. At the point 6 on the beater-frame an actuating gear wheel 7 is pivoted, and this gear wheel is rotated by means of a crank 8 and handle 9.

Attention is called to the fact that the substantially U-shaped portion of the frame is squared at the points 10 and 11 and right angles formed at the junction of the vertical walls 3 and 4 and the horizontal wall 85 5. These right angles are formed in the frame for the purpose of giving rigidity and strength to it to take up and compensate for the strains which are put upon this frame during the operation of the actuating 90 gear-wheel and beater blades hereinafter to be described.

At the center of the vertical wall 3 of the beater framework there are two portions 12 struck out of the outer surface, and one portion 13 on the inner surface, the portion 13 being between the two portions 12. The other vertical wall 4 is similarly provided with two outwardly struck portions 14 and one inwardly struck portion 15. In addition, however, the upper edge of the vertical wall and integral with the upper struck out portion 14 is provided a horizontally extending lip 19 providing a stop for the upper end of the beater supporting wire herein- 105 after to be described. These struck out portions are for the purpose of receiving the upper ends of a substantially U-shaped supporting wire 16 upon which beater blades 17 are mounted, carrying at their upper ends 110 and adjacent the lower edge of the vertical members 3 and 4 gear-wheels 18 which mesh

with the actuating gear 7. The upper portion of the two ends of the wire support 16 are flattened so as to be of rectangular cross section as shown at the point 20. It is to be understood however, that these wires may be flattened to present any number of sides without departing from the spirit and scope of the present improvement. This portion 20 is of a length equal to the combined lengths of the struck out portions carried by the vertical portions 3 and 4. Due to the shape of these wires when they are once inserted between the struck out portions, they will be held rigidly and can not be twisted or rotated in the struck out portions as would be the case were they of circular cross section as is the remainder of the supporting wire 16. No specific claim is made herein upon the beater-blades 17 or their specific connection with the gears 18, as this manner of making beater-blades and this way of connecting them is old in the beater art. Particular attention, however, is called to the specific manner of arranging the struck out portions upon the vertical walls 3 and 4. Due to the arrangement of these struck out portions as shown, the upper ends of the supporting framework wire 17 are securely clamped and when this wire is put under the stress of the rotating beater-blades, it cannot be bent or twisted sidewise but will remain perfectly rigid and will insure at all times a perfect alinement of the small gears 18 with the large actuating gear 7.

The foregoing description relates and describes the smaller form of beater which is adapted for ordinary household use, but when the beater is made of a greater size to facilitate its use in hotels, bakeries, etc., the construction of the beater blades supporting wires is different, and the description of this modification will now be taken up.

Referring to Fig. 4, it will be seen that the lower U-shaped portion of the beater framework is of substantially the same construction as shown in Fig. 1, and the assembling of the upper ends of the U-shaped supporting wire with the struck out portions is also identical with that shown in Fig. 1. In this modified form of beater, however, an additional supporting wire 21 is provided which is of substantially a U-shape, the upper ends 22 thereof being fastened within the horizontal portion 5 of the beater framework in a specific manner hereinafter to be described. The supporting wire 16, unlike its construction in Fig. 1, is deeply notched at the point 25 forming a seat for the auxiliary supporting wire 21. Extending ends 23 and 24 are formed on each side of the notch 25. At the point 26 the auxiliary supporting wire 21 is flattened on its top and bottom for the purpose of assisting in receiving a clamp 27, which is of the shape of a cross, the legs of the cross being of sufficient shape to be bent in their centers and thence up and around the two ends 24 of the supporting wire 16 and also around the supporting wire 21 adjacent its junction with the ends of the supporting wire 16. This clamp firmly locks these two wires together and at the same time also clamps the ends 23 and 24 of the supporting wire 16 together. Due to the deep notch in the beater blade supporting wire the bottom of the beater support is nearly as flat in the modified construction as in the construction shown in Fig. 1. This is due to the fact that the supporting wire 16 is deeply notched as before described.

The specific manner of attaching the upper ends 22 of the auxiliary supporting wire 21 consists in first cutting a V-shaped notch 28 in the periphery of the wire and then passing the wire through a hole 29 formed in the horizontal surface 5 of the framework. After the ends 22 are in position in the holes 29, they are struck with a tool at the point 30 and the metal of the horizontal portion 5 driven into the notch 28 as is shown in Fig. 6. This construction forms a positive lock for holding the end 22 in the same position relative to the horizontal portion 5 and will prevent it from either slipping up or down out of the holes 29.

From the foregoing description, it will be seen that I have evolved a cheap and simple beater framework which when assembled will never come apart through use of the beater, and will at all times be so rigid and fixed that the actuating means for the beater-blades will always be in true alinement one with the other, and that the framework will not be twisted and thereby clog the gears.

Having thus fully described my invention what I claim and desire to secure by Letters Patent is:

1. An improved beater comprising a framework, a beater blade supporting wire, the upper ends of the said wire secured to the framework, an auxiliary beater supporting wire, the upper ends of the said wire fastened to the framework, the lower end of the auxiliary beater supporting wire crossing the beater blade supporting wire, a clamp providing means for fastening the two said wires together, beater blades carried by the beater supporting wire, and actuating means carried by the said framework.
2. An improved beater comprising a framework, a beater blade supporting wire, the said wire carried by the framework, an auxiliary beater supporting wire carried by the framework, the said auxiliary wire crossing the beater supporting wire and a cross-shaped clamp fastening the two said wires together at the point of crossing, beater blades carried by the beater supporting wire, and actuating means carried by the framework.

3. An improved beater frame, having a U-shaped lower end and a handle at its upper end, the vertical walls of the U-shaped end having intermediately outwardly struck 5 angular-shaped portions, and beater wires with angular-shaped tops corresponding to the angular struck outward portions, whereby the beater frames are supported against twisting movement, and means for preventing the upward movement of the beater frames.

4. An improved beater comprising a framework, a beater blade supporting wire carried by the said framework, an auxiliary beater 15 supporting wire carried by the said framework, the beater supporting wire provided with a notch, an auxiliary beater supporting wire crossing the beater supporting wire and fitting in the said notch, a clamp fastened to 20 the said wires adjacent their point of crossing, beater blades carried by the beater supporting wire, and actuating means carried by the framework.

5. An improved beater framework having a 25 lower U-shaped end and a handle at its upper end, the vertical parallel portions of the U-shaped end each having a plurality of outwardly struck angular-shaped portions and outwardly struck lip above the angular portions, and beater frames having angular upper ends fitting in the angular-shaped portions with their upper ends below the outwardly struck lip to prevent the frame twisting and having vertical movement.

35 6. An improved beater comprising a framework, the said framework consisting of a substantially vertical body portion, the lower end of the said body portion bent and doubled upon itself so as to form two vertical 40 walls and one horizontal wall, the said vertical walls meeting the horizontal wall at right angles thereto, the two vertical walls each provided with three struck out portions intermediate their ends, two of the struck out 45 portions extending on the outside of the

vertical walls and one struck out portion intermediate the two aforementioned struck out portions extending on the inside of the vertical walls, the struck out portions shaped to form an angle, a substantially U-shaped 50 beater supporting wire, the ends of the said wire of angular cross section, said ends fitting within the struck out portions, beater blades carried by the said wire, the said angular portion of the wires and angular opening 55 preventing the movement of the blades from twisting the wires, the said framework held rigid by the walls thereof meeting at right angles to each other, and an actuating means carried by the vertical portion of the framework, and a handle carried by the said framework.

7. An improved beater comprising a framework, a beater blade supporting wire carried by the said framework, an auxiliary beater 65 supporting wire carried by the framework, the two said wires crossing each other, a clamp having four members each member being fastened to one of the wires adjacent their crossing point, beater blades carried by 70 the beater supporting wire, and actuating means carried by the said framework.

8. An improved beater comprising a framework, a beater blade supporting wire carried by the framework, an auxiliary beater supporting wire carried by the framework, the two said wires crossing each other, a clamp having four radial arms grooved throughout 75 their length and curved around each wire to grip it adjacent the crossing point, beater 80 blades carried by the beater supporting wire, and actuating means carried by the said framework.

In testimony whereof I hereunto affix my signature in the presence of two witnesses. 85

LAVERN BORDWELL.
